[57] CLAIM

The ornamental design for a pneumatic tire tread and
buttress, substantially as shown and described.

DESCRIPTION

FIG. 1 is a perspective view, partly schematic, of a
pneumatic tire tread and buttress embodying my new
design, it being understood that the pattern is repeated
throughout the circumference of the tread and but-
tress, as shown schematically by solid lines, and that the
buttress pattern is repeated on the opposite side;
FIG. 2 is an enlarged, fragmentary developmental plan
view of the tread and buttress of FIG. 1; and
FIG. 3 is an enlarged sectional view of the tread and
buttress, taken substantially as indicated by line 3—3 of
FIG. 2.

Fig. 1.
